HEATER.

APPLICATION FILED APR. 27, 1921.

Patented Dec. 5, 1922.

UNITED STATES PATENT OFFICE.

EUGENE A. MERRILL, OF ALHAMBRA, CALIFORNIA.

HEATER.

Application filed April 27, 1921. Serial No. 465,953.

To all whom it may concern:

Be it known that I, EUGENE A. MERRILL, a citizen of the United States, residing at Alhambra, in the county of Los Angeles 5 and State of California, have invented new and useful Improvements in Heaters, of which the following is a specification.

This invention relates to a heater of the type employed in hot air heating of rooms 10 and particularly pertains to a heater of this class which is adapted to the burning of gas as a fuel.

An object of this invention is to provide a sectional heater in which one or more 15 complementary units may be employed to form a heater of any desired capacity and embodying a construction whereby two or more of the units may be readily assembled and securely joined together.

Another object is to provide a heater of 20 the above character in which hot products of combustion may be caused to traverse a large radiating surface in a compact space throughout a heater unit and thereafter delivered to a vent stack whereby a maximum 25 of heating effect may be obtained with the consumption of a minimum of fuel.

Another object is to provide a heater unit which is so formed that when two or 30 more corresponding units are arranged face to face, a combustion chamber in one unit will open throughout its cross sectional area with the combustion chamber of the adjacent unit to provide a continuous chamber 35 through the successive units and whereby any desired length of combustion chamber may be obtained by assembling a suitable number of units.

A further object is to provide a simple 40 means for fastening a series of the units together collectively whereby they may be easily assembled and dis-assembled.

Other objects will appear hereinafter.

The invention is illustrated by the accompanying drawings in which:

Figure 1 is a view in side elevation of a heater constructed in conformity with the invention showing a part of the casing broken away to reveal the combustion chamber 50 and burner.

Figure 2 is a view in end elevation of the heater showing the front or burner end.

Figure 3 is a view in end elevation of the heater showing the rear of flue end thereof.

Figure 4 is a view in elevation and partly in vertical section of one of the heater radiating units.

Figure 5 is a view in vertical section as seen on the line 5—5 of Figure 4.

Figure 6 is a view in vertical section as seen on the line 6—6 of Figure 4.

Figure 7 is a view in perspective of the front end plate.

Figure 8 is a view in perspective of the back end plate.

Figure 9 is a diagrammatic sectional view illustrating the preferred manner of installing the heater.

More specifically 10 indicates a heat radiating unit which embodies an upper portion 70 comprising a pair of spaced vertical end walls 11—12 joined at their vertical edges by side walls 13—14 and at their upper edges by an arcuate top wall 15. A pair of spaced partitions 16—17 extend between the end walls and are spaced from the side walls with their upper ends terminating a distance from the top wall; thus forming the interior of the upper portion of the radiating element with a central chamber *a*, end 75 chambers *b*—*c*, and a top chamber *e*; these chambers constituting passages for conveying products of combustion as will be later described. The unit is formed with a base portion comprising a bottom wall 18 and 80 side walls 19—20; the side walls extending upwardly from the bottom wall in arcuate form and provided with forked portions of semi-circular form one part of which extends in continuation of the side walls 90 13—14 and the other part of which connects with the lower ends of the partitions 16—17 forming bottom walls 21—22 for the chambers *b*—*c*. The base portion is open 95 at its ends throughout the area bounded by the bottom wall 18, side walls 19—20, the inner portions of the walls 21—22, and the lower ends of the end walls 11—12. This area constitutes a combustion chamber *f* which is in open communication with the lower portion of chamber *a*. The end walls 11—12 are formed with aligned 100 openings 23 located at the lower portion of chamber *b* and with corresponding openings 24 arranged at the lower portion of chamber *c*, these openings with the walls 21—22 forming transverse passages through the unit communicating with

105

the chambers *b-c* and separated from the combustion chamber by the inner portions of the walls 21-22.

Formed on the opposite ends of the unit 5 and bordering on the margins of the chamber *f* and openings 23-24 are flanges 25-26; the flange 26 being formed with a tapered lip 27 and the flange 25 having a recess 28 throughout its inner wall to receive the lip 10 27 of an adjacent unit.

Formed in the walls 11-12 adjacent their upper ends are openings 29-30 having marginal flanges 31-32; the flange 31 having a recessed inner wall 33 to receive a lip 15 34 on the flange 32 of an adjacent unit; these openings being provided to receive a tie rod 35 by which the upper portions of a series of the units may be connected together, and formed in the end walls 19-20 20 are recesses 36-37 to accommodate tie rods 38-39 by which the lower portions of the units may be connected together.

Front and rear end plates 40-41 are provided for closing the openings in the lower 25 or base portions of the end units and also afford walls between which the units may be securely held as will be later described; the front plate 40 being formed with a lip 42 adapted to extend into the recess 28 of 30 a unit and the rear end plate having a channel 43 to receive the lip 27 of a unit. The front plate is formed with an opening 44 to receive a tubular burner 45 and has secondary air inlet openings 46-47 arranged 35 on opposite sides thereof to open to the combustion chamber *f*. The rear end plate is formed with a chamber 48 adapted to communicate at its ends with the openings 23-24 of a unit which chamber opens upwardly through a tube 49 to which a vent stack 50 may be connected, and has a cold air inlet 51 opening to the underside thereof 40 below the tube.

The burner 45 is here shown as comprising 45 a horizontally disposed gas-pipe 52 provided with a plurality of small holes 53 placed midway between the ends, and a tubular burner 54, surrounding the gas pipe and provided with a series of burner orifices 55 50 throughout its upper surface. A space 56 between the gas pipe and the burner body constitutes a distributing chamber for gas and air which are mixed before issuing from the gas pipe and for this purpose the forward 55 end of the gas pipe passes out through the opening 44 in the front panel and extends into a cage fitted with an air regulating shutter 57. A valve 58 is provided for regulating the flow of gas to a nozzle opening 60 into the cage opposite the open outer end of the gas pipe. A pilot flame feed line 59 is tapped into the valve and passes through the panel into the combustion space, above the burner body.

65 The burner body is formed of such length

as to extend throughout the length of the combustion chamber and to abut against the rear end plate; the forward end of the burner being formed with a shoulder 60 adapted to abut against the outer face of 70 the front end plate. The gas-pipe is formed of such length as to extend through the rear end plate and its rear end is threaded to receive a cap 61 which when screwed on the pipe will abut against the outer face of the 75 rear end plate and coact with the shoulder 60 in holding the burner in position between and supported upon the end plates. The end plates may be formed integral with the end units. 80

In assembling the heater any desired number of the units are arranged end to end in a row as shown in Figure 1 with the lips 27-34 of one unit extending into the recesses 28-33 of the adjacent unit, a suitable 85 packing being placed in the joints to effectively seal them. The tie-rod 35 is inserted through the aligned openings 29-30 and through caps 62-63 seating on the flanges 31-32 of the outermost units, and a nut 64 is 90 screwed on one end of the rod to oppose a head 65 on the other end thereof and tightly clamp the upper portions of the units together. The end plates are then placed in position and the tie-rods 38-39 passed 95 through openings formed in the end plates to receive them and nuts 66 screwed on the rods in opposition to heads 67 thereon to draw the end plates toward each other and securely clamp the units therebetween. It 100 will be observed that when a series of the units are thus joined together the combustion chambers of the units will intercommunicate and form a single combustion chamber throughout the length of the heater between 105 the end plates, and that a continuous passage will unite the lower portions of each of the chambers *b-c* and connect them with the vent stack.

The burner is then put in place as before described, being disposed to extend throughout the length of the combustion chamber adjacent to the bottom wall thereof.

The operation of the heater is as follows: A pilot flame is maintained so that upon 110 opening the gas valve gas enters and passes into the mixing chamber and draws in air through the air shutter cage in the manner common to such burners and the mixture of air and gas issues from the burner orifices to 115 the combustion space where it is ignited by the pilot flame.

As the products of combustion rise upward secondary air is introduced through the secondary air openings 46-47. These air 120 openings are substantially on a horizontal plane with the burner so that the air flows throughout the length of the combustion chamber and is delivered laterally toward the burner from opposite sides thereof caus- 125 130

ing two columns of air to impinge on the burner body; whereupon they are caused to rise around the flame jets to supply the burning gas with additional oxygen. This relative arrangement of secondary air passages and burner results in a positive supply of secondary air to the flames but without undue velocity so that burning gases and secondary air intimately mingle to promote complete combustion. The hot products of combustion rise through the chamber *a* of each of the units into the chambers *e* and pass downward through the chambers *b*—*c* and then pass to the vent stack as before explained, and act in their passage to highly heat the walls of the heater which afford a large heat radiating area.

The heater may be installed below the surface of a floor 68, as illustrated in Figure 9, and fitted with a hood of any suitable form adapted to collect the air that is heated by the heater to deliver it to the room and is here shown as comprising an outer casing 69 from the top of which a hot air duct 70 passes up to a grating 71 in the floor. The lower end of the casing has air inlets 72. An inner casing 73 surrounds the heater and is open at the top and bottom so that warm air is drawn from below and takes the path indicated by the arrows. The vent stack 50 is connected to the end panel of the heater to carry off the products of combustion so that they do not enter the room.

While I have shown and described a specific embodiment of my invention, I do not limit myself to the exact details of construction shown, or the arrangement of parts, but may employ such construction or combination of the salient features of the invention, coming within the scope of the appended claims, without departing from the spirit of the invention.

I claim:

1. A heater unit comprising an upper portion enclosed by side walls, end walls and a top wall, a pair of spaced partitions extending between the end walls terminating below the top wall and connecting at their lower ends with the side walls forming said upper portion with a middle chamber and side chambers communicating therewith, the end walls being formed with openings at the lower ends of the side chambers adapted to register with corresponding openings on an adjacent unit, and a base portion enclosed by side walls formed in continuation of the side walls of the upper portion and open at its ends, and communicating with the middle chamber; said base portion forming a combustion chamber adapted to open to a corresponding chamber in an adjacent unit.
2. A heater comprising a series of complementary units each embodying a base portion having a bottom wall, side walls and open at its ends and adapted to have open communication with the interior of the base portion of an adjacent unit to form a combustion chamber throughout the successive units; each unit having an upper portion enclosed by side walls, end walls, and a top wall formed with spaced partitions extending between the end walls terminating below the top wall and connecting at their lower ends with the side wall; the end walls being formed with openings communicating with the space between the partitions and the side walls adapted to register with the corresponding openings on an adjacent unit to form continuous passages through the successive units separated from the combustion chamber adjacent thereto; the space between the partition walls opening to the interior of the base portion whereby products of combustion may rise from the base portion into the upper portion; a pair of end plates, and means connecting the end plates for clamping the units together between the end plates.
3. A heater unit comprising a base portion formed with a bottom wall and side walls and open at its ends forming a combustion chamber; a heat radiating upper portion enclosed by side walls, end walls, and a top wall, having a central chamber opening at its lower end to the interior of the base portion and connecting its upper end with downwardly extending side chambers; the end walls of said upper portion being formed with openings communicating with said side chambers at the lower portions thereof, the margin of said openings and the ends of the base portions being formed on one side of the unit with a lip and on the opposite side of the unit with a recess adapted to receive the lip of an adjacent unit.
4. In a heater, a series of complementary units each having a base portion formed with a bottom wall and end walls arranged with the interiors of adjacent base members in open communication with each other; each of the units being formed with an upper heat radiating portion enclosed by side walls, end walls, and a top wall, the interior of the upper portion being divided into a central chamber and side chambers opening to the upper portion of the central chamber; said central chamber being in open communication with the interior of the base member and the lower portions of the side chambers communicating with the lower portions of the side chambers of an adjacent unit forming passages through the successive units, front and rear end plates between which the base portion of the units are interposed, tie rods connecting the end plates, a burner located in the space bounded by the base members; said front end plate having air inlet openings and said rear end plate formed with a chamber communicating with

the passages of the end unit, and a vent stack leading from said chamber.

5. A gas heater comprising a burner and an assembled casing made up of a plurality 5 of casing members fitted together said casing members each formed with a combustion space and a vertically disposed radiating space which is closed at the top but communicates at the bottom with the combustion 10 space, said casing further formed with vertically disposed flue passages communicating with said radiating space adjacent its top; whereby products of combustion

pass from said combustion space upward through said radiating space to enter said 15 flue passages and pass downward through said flue passages in proximity to the walls of said casing, means for connecting said flue passages to the flue passages in adjacent 20 casing members and means for connecting the combustion spaces in adjacent casing members to form a substantially continuous combustion space throughout the assembled casing members.

EUGENE A. MERRILL.
